UNITED STATES PATENT OFFICE.

HARRY D. FOSTER, OF WASHINGTON, DISTRICT OF COLUMBIA.

BUILDING BLOCK OR TILE CONSTRUCTION.

Application filed June 14, 1926. Serial No. 115,840.

This invention relates to improvements in unit blocks or tiles for building construction, and more particularly bears upon the shapes of such units for erecting load bearing walls or partitions which are to be used for fire, party or division walls and exterior walls, in that the design of the unit makes possible a more fire-resistant and moisture-proof wall than has heretofore been attained.

10 It has heretofore been proposed to prepare such units in various forms and to assemble them in various manners, whereby walls are produced for buildings. It has been customary to make tiles by an extrusion process, the material for the tile being contained in a machine hopper from which it is forced through a die having cores therein. These dies and cores are so regulated and arranged in shape and dimensions that a long continuous tube is

15 produced which is cut off to predetermined lengths to form the green tile which is thereafter dried and baked or burned to be rendered stable in shape and to impart to it the necessary characteristics of strength for use.

20 25 It is customary in the trade to refer to the sizes of the tile which are to be exposed to the outside and inside of a wall in straight run work as the "face shells" or "outer shells". The members connecting the ends of these face shells are referred to as "cross shells". The members in the interior of the tile which connect and brace these members and form individual air chambers in the tile are called webs, and may extend between the face shells (cross webs) or parallel to the face shells ("longitudinal webs").

30 35 It is necessary to have the webs as thin as possible, so that the drying and baking may occur quickly and to reduce the weight and quantity of material while obtaining the highest possible efficiency of the material used in the wall.

40 45 Such units have heretofore been proposed with apertures of various sizes and arranged in various relations to each other to produce a structure having one or more rows of apertures extending therethrough. It is customary in assembling such units to form a wall to lay them with the cells either horizontal or vertical and in general communication with the corresponding cells of the adjacent units. Mortar is placed upon the upper surface of each unit along the ends of the face shells and on the cross shells and webs: mortar is likewise placed on the ends or outer faces of the

cross shells, so that mortar joints join the unit with the adjacent units on all sides of it. For the vertical joint, when the cells are arranged vertically, only narrow strips of mortar were placed in prolongation of the outer faces or shells, while when the unit was laid with the cells horizontal, a full bed of mortar was placed on the tile, thus causing transmission of the load of the superimposed wall and superstructure from tile to tile through this mortar joint and upon the cross shell, so that the latter oftentimes was ruptured, and for the vertical joint with the shells horizontal the mortar was placed only in prolongation of the outer faces or shells with no attempt to place mortar on the web at the center of the wall. The air chambers were therefore never sealed one from another.

50 55 Units heretofore designed have usually had a single thin web at the center which was too narrow to support the mortar to form a seal: the air chambers separating adjacent central webs were so wide that the mortar fell through and was not held in position to establish the seal.

60 65 According to the present invention, a shape of unit is provided in which two continuous air chambers, separated from each other and when assembled in the wall maintained independently sealed from each other both in the horizontal and vertical joint and from which the atmosphere is excluded, and furthermore the inner webs of the unit are so allocated that a joist may have more than one bearing upon the unit, whereby it will be 70 steady and held in invariable position, and does not interrupt the continuity of the seal of at least one of the air chambers. In this way, a wall construction is provided which is better adapted as a heat insulator than prior 75 walls, inasmuch as a plurality of separate air chambers are assured, and furthermore in the event of a conflagration at least one full and sealed air chamber remains to prevent the passage of flame and heat through the wall, 80 even in the event of a total destruction of the part of the wall upon which the joists are supported.

85 90 95 A further feature is the provision of a block or tile in which the cross shells are relieved of transverse load by reason of the mortar joints, more particularly when the block or tile is placed with its air chambers horizontal.

100 105 110 While the foregoing statements have re-

ferred more particularly to clay units, yet it will be understood that the unit may be fashioned of any other material with which, for reasons of lightness or economy, it is essential that the shells and webs be made as thin as possible.

In the drawings are represented two forms of the unit, and two methods of assembling such units in walls, but it will be understood that these are merely by way of illustration and not intended as the sole examples of forms in which the present invention may be employed.

Figure 1 is a perspective view of a preferred form of such a unit or block.

Fig. 2 is a perspective view of a wall formed by disposing a plurality of such units with their individual air chambers in vertical position.

Fig. 3 is a similar perspective view of similar units employed in wall construction with the air chambers disposed in a horizontal position.

Fig. 4 is a perspective view of a modified form of the unit.

In these drawings, in Fig. 1 the preferred form of the unit is represented as having the two external faces or shells 10 and 11 which are connected by a series of inner transverse webs 12 and the cross shells 13. It will be understood that the outer members 10 and 11 are usually of greater thickness than the webs and cross shells, as is now customary in the art. A peculiarity of the present unit is the provision of two inner webs 14 which are in substantial parallelism with the face members 10 and 11 and are of approximately the same thickness as the cross webs and shells, 12 and 13: these inner longitudinal web members 14 are separated from each other by the narrow apertures 15, and are separated from the face members or shells 10 and 11 by the wider apertures or air chambers 16. In the style of unit illustrated, which may be of the customary dimensions of 12 inches square for the face members 10 and 11, and a thickness between the outer faces of the face members of eight inches, three rows of apertures are provided, but it will be understood that the invention is not limited to any specific number of such rows in the longitudinal direction of the tile or in the thickness of the unit.

The distance between the longitudinal webs 14, i. e., the width of the apertures 15, is such that the mortar, in its usual consistency, is held by adherence against the walls and by its internal coherence, in a proper position to form a closed seal between the walls 14 of the abutting units.

On the ends of the unit, the face members 10 and 11 extend beyond the cross shells 13 to provide the edge flanges 17. Intermediate the length of the cross shells 13 and in substantial alinement with the longitudinal webs 14 are provided the ribs 18 which are vertical

in the position shown in Fig. 1 and have a channel 19 between them to receive mortar when assembled in a wall.

The method of employing such units is shown in Figs. 2 and 3. In Fig. 2, the air chambers 16 are arranged in a vertical position, and as the units are assembled in the wall the horizontal lines of mortar 20, 20 are placed upon the ends of the shells or face members 10 and 11 to form the usual mortar joints for the inside and outside of the wall. In addition to this, a line of mortar is placed upon the longitudinal webs 14, 14 as represented at 21, which acts in conjunction with the longitudinal web members 14, 14 of the superimposed unit to form a continuous seal between the two rows of air chambers 16, so that there are three separate mortar joints formed in the thickness of the wall. The presence of the apertures 15 permits the mortar to enter slightly into the depth of the unit so that the mass of mortar is prevented from falling off from the edges of the webs 14. It will be noted that mortar joints are not formed on the cross webs and shells 12 and 13 but interruptions occur so that no continuous mortar joint is formed from one face of the wall to the other: this prevents the ready passage of moisture through the wall by capillarity in the porous mortar.

In placing the units, likewise, mortar is placed in the customary manner upon the edge flanges 17, to form sealing joints with the abutting unit of the same course, and in addition thereto mortar is placed in the groove 19 and upon the ribs 18. The keying of the mortar in the groove 19 prevents it from being discharged or scaled off from the narrow ribs 18 while being placed in position in the wall. It will thus be seen that there are likewise provided three lines of mortar joints in the wall at each vertical joint, which are designated as 22, 22 and 23 in Fig. 2.

A joist such as J in Fig. 2 may be seated upon any course of the units, and the course next above the course chosen as a support is formed by the usual units in the usual way until the point of the joist is reached, at which point a unit is employed which has been broken in half longitudinally on the portions of the cross webs and shells 12 and 13 extending between the longitudinal webs 14 to form the apertures 15. One row of the air chambers 16 is therefore left intact, at the side of the wall opposite that at which the joist J is received. The joist J enters the wall for substantially half its thickness and receives a solid and firm bearing upon an outer face member or shell 10 and one of the longitudinal webs 14. The space alongside the joist, between it and the adjacent units, is then filled by the small sections S formed of broken units, preferably maintaining air chambers from top to bottom, and the space above and around the joist is filled until a solid wall is

obtained. As customary, the air chambers at the inner side of the wall in the course above and below the joint course may be filled up with mortar to seal the wall, and prevent any passage of air into the air chamber around the joists.

The joist F is shown with a beveled end, the intersection of the bevel with the top of the joist occurring substantially at the faces 10 of the units.

In the event of a fire occurring on the inner or near side of the wall represented in Fig. 2, in which the portions of the joists J supporting the floor are consumed, the joists may fall and the bevel cuts will prevent any raising or cracking of the superimposed wall: the remaining row of air chambers 16 will prevent a substantial passage of heat through the wall, so that the exterior of the wall will remain cool and will not be damaged by the throwing of a stream of water thereupon. At the same time, while the throwing of water upon the heated interior face of the wall might on one occasion result in scaling, as is known today, this scaling will merely involve the separation of portions of the face members 10 on the inner side of the wall, with the exposure of the air chamber 16 at this face of the wall, but without opening the air chamber 16 at the other side of the wall, since the central seals 21, 23 remain unimpaired; usually not more than a small portion of the air chambers 15 intermediate the same are opened. It will be noted that the air chambers 15 of the individual units are sealed at top and bottom in the course of the construction of the wall, so that there is very little opportunity for heat to pass through them even when the inner face members 10 have been scaled off as indicated above.

The construction of wall shown in Fig. 3 is very similar, except that the units are respectively arranged in a position in which their air chambers are horizontal. It will particularly be noted in regard to this figure that the three lines of mortar occur respectively above the thickened face members or shells 10 and 11, and above the doubled longitudinal webs 14, and that the gaps between the mortar joints 20 and 21 will prevent a solid contact through the mortar between the weak cross shells 13 of the unit. The entire load of the wall is carried in the line of the mortar joints and upon the longitudinal web and face members which extend the full length of the unit, so that there is no tendency to crack the cross shells by transverse loads thereon. A similar seal is effected by the vertical joints, which are likewise restricted in width so that gaps exist between them and moisture cannot pass immediately from the inner to the outer face of the wall or vice versa. This is true likewise at the points of insertion of joists J.

This modified form of wall construction en-

joys the same advantages of safety against entire disruption in the event of a fire. At least one row of air chambers is always preserved even though the row adjacent the combustible matter may be entirely open by scaling of the face shells on that side, and it is usual that very few of the air chambers 15 are open. It will be noted that with this construction also the air chambers are individually sealed for the individual units. It is preferable to seal the air chambers adjacent the joist so that even if the joist be removed, the atmosphere has no access into the interrupted series of air chambers.

In the modified form of the unit shown in Fig. 4, the air chambers 16^a are provided and are separated at the middle of the unit by two longitudinal webs 14^a which converge toward the center of the tile and there form a common point of intersection with the web member 12. Although the present illustration is of a unit having a single web member 12, it will be understood that more than one such web may be provided if desired. The other elements are the same as in Fig. 1. This shape is particularly adapted for thin partition units.

In this modified form of construction, the intermediate apertures 15^a between webs 14^a and cross shells 13^a are triangular in section and serve for the same purpose as in Fig. 1. The relative sizes of the parts are such that a joist is supported upon a portion of a web 14^a as well as upon the shell or face member 10. The mortar which is applied upon the longitudinal web members 14^a is supported as with the first example, and at the thinnest portion, the center, it is likewise supported by the cross web 12. In case of a fire, the mortar joint will prevent the passage of fire into the air chamber 16^a.

While the invention has been described in connection with a standard unit and a modified form of unit intended for partition use, it will be understood that it is not limited thereto, but units with any size of face and any thickness of wall, so that any number of air chambers may be employed in conjunction with any number and arrangement of successive longitudinal and cross webs.

It is apparent that the invention is not limited to the specific employment set forth by way of illustration, but that it may be modified within the scope of the appended claims.

I claim:

1. In a hollow wall, a plurality of integral hollow units each having mortar-supporting face shells and a plurality of cross and longitudinal shells and webs, said cross and longitudinal shells and webs being individually incompetent to sustain mortar, two of said longitudinal webs being arranged close together whereby to sustain mortar, said units also having end projections on said cross

shells in the line of said face shells and longitudinal webs whereby to support spaced mortar joints, and spaced mortar joints on said face shells and juxtaposed longitudinal webs and on said end projections to connect said units, whereby at least two independently sealed and separate air chambers are formed in the wall intermediate its faces.

2. In a hollow wall, a plurality of integral hollow units each having face shells and a plurality of internal longitudinal webs and connecting cross shells, and a plurality of spaced mortar joints on said face shells and longitudinal webs to connect said units, certain of said units being cut away through one face shell and one longitudinal web whereby to present a support for a joist member upon the corresponding face shell and longitudinal web of the unit beneath, said mortar joints sealing the chamber formed between the other face shell and the adjacent longitudinal web independently of such cut-away portion whereby a fully-sealed air chamber is located between the end of the joist and the other face of the wall.

3. In an integral hollow building unit, thick face shells adapted to support mortar for the external mortar joints, a plurality of thin longitudinal webs located between and substantially parallel to said face shells, said webs being spaced from said shells and located close one to another so that they can sustain mortar for an internal longitudinal mortar joint independent of said external

35 joints, thin cross-shells connecting and supporting said face shells and longitudinal webs with respect to each other, wide marginal projecting flanges on the exterior of the cross-shells in the planes of the face shells to support mortar for the external mortar 40 joints, and intermediate ribs on the exterior of said cross-shells opposite the junctions with the longitudinal webs to support mortar for the internal longitudinal mortar joint.

4. In a hollow wall a plurality of integral 45 units arranged in the wall to form a plurality of successive air chambers between the face of the wall and having face and cross shells and longitudinal webs parallel to and between the face shells, external mortar joints 50 in the planes of said face shells to connect said units and close said air chambers to the exterior of the wall, and an internal mortar joint in the plane of said longitudinal webs and independent of said external joints to 55 separate said chambers from one another, said cross shells being so thin that no mortar joints can be formed thereon to permit seepage of moisture between the faces of the walls, said cross shells having external projections thereon in the planes of said face shells and longitudinal webs to receive and transmit loads from one unit to the next and being spaced apart so that no mortar body 60 can remain to transmit such loads directly 65 between the cross shells.

In testimony whereof, I affix my signature.
HARRY D. FOSTER.
